UNITED STATES PATENT OFFICE

2,457,007

ELECTRIC RANGE SURFACE UNIT

Ernest E. Sutherland, Mansfield, Ohio, assignor
to Westinghouse Electric Corporation, East
Pittsburgh, Pa., a corporation of Pennsylvania

Application December 2, 1946, Serial No. 713,516

2 Claims. (Cl. 219—37)

1

This invention relates to electric range surface units, and has for its object the provision of an improved device of this character.

In a prior construction, an annular support ring was so constructed as to nest in a circular opening in the platform of an electric range. Upon an inwardly-disposed flange in this support ring, a reflector pan with an outwardly-disposed flange was supported. A heater unit comprising a plurality of tubular sheathed heaters supported by a spider was also supported by the support ring flange in a horizontal position. To swing the heater unit in a vertical arcuate movement to permit removal of the reflector pan for cleaning, use was made of a U-shaped member which pivotally supported the terminal portions of the heater during this operation. This U-shaped member was so constructed as to hinge at one end and lock in position at the other end. However, to completely remove or replace the heater, it was necessary to unlock the U-shaped member by removing a nut and screw. This allowed the bracket to be swung away, by rotating at its hinge point, to clear the heater terminal portions. Such an operation was tedious and difficult to perform.

It is an object of this invention to provide an electric heating unit in which the heater unit can be more easily and quickly replaced or removed.

In accordance with the present invention, a bracket of inverted T shape is used instead of the U-shaped bracket. The T-shaped bracket is so formed that its vertical portion is disposed in the space between two adjacent terminal portions of the heater. The crossbar of the T-shaped bracket is disposed below the two adjacent terminal portions of the heater mentioned above. When the heater unit is lifted upwardly as described, for cleaning, the crossbar pivotally supports the heater at its terminal portions. If the heater is to be removed entirely from the surface unit, the T-shaped bracket does not have to be removed, since by lifting and rotating the heater the crossbar may be cleared of the obstructing terminal portions, and the heater may be removed.

In the accompanying drawings,

Fig. 1 is a top plan view of a device embodying this invention;

Fig. 2 is a cross-sectional view taken along line II—II of Fig. 1;

Fig. 3 is a fragmentary bottom view showing details of construction;

Fig. 4 is a fragmentary sectional view show-

2

ing the heater unit in a raised position supported by the crossbar of the inverted T-shaped bracket and further showing the reflector pan in process of being removed;

5 Fig. 5 is a fragmentary perspective view showing a portion of the support ring alone with the inverted T bracket attached; and

Fig. 6 is a top perspective view of the device, with the reflector pan removed, showing method 10 of removal of the heater unit.

Referring to the accompanying drawings, in the illustrated embodiment I provide a heater unit 10 which comprises tubular sheathed heaters 11 and 12, and a spider 13 to which the 15 tubular heaters are fastened. An escutcheon plate 14 is also attached to the spider. Each tubular heater comprises a resistance wire 15 embedded in insulation material 16 and surrounded by a tubular metal sheath 17. The effective portions of the tubular heaters are disposed substantially in a horizontal plane. The terminal portions, however, extend downwardly and then horizontally to a terminal block assembly 18. Power leads 19 are connected to the terminal block assembly in a conventional manner.

An annular support ring 20 rests on a flange 21 formed in the platform 22 and surrounding the opening 23 in the platform. The ring 20 is formed with an inwardly-extending flange 24.

30 A reflector pan 25, which acts as a heat reflector and also as a food and crumb collector, has its peripheral portion or flange resting on the flange 24. The flange 24 also supports the heater unit 10 when the latter is in its normal operating 35 position, the outer ends of the spider arms normally resting on the peripheral portion of the reflector.

As best shown in Figure 4, a bracket 26 of inverted T shape is rigidly fastened to the support ring 20 in any suitable manner, in the 40 position shown. The bracket 26 has a vertical portion 27 and a crossbar 28. Referring to Figures 2 and 3, the bracket is seen to have its vertical portion 27 disposed between two adjacent terminal portions 29 and 30 and its crossbar 28 disposed below said two terminal portions.

In order to latch the heater unit 10 in normal 45 operative position in the support ring 20, the spider 13 and the ring 20 are formed with co-operative interlocking portions, as shown at 31 in Figure 2. Such interlocking portions comprise a notch or cutout in the end of the spider arm and an extruded portion in the ring. A tension spring 32 is provided to bias the heater 50 unit to the left to maintain the interlocking por-

tions in engagement. One end of the spring is connected to the lower end of the T-shaped member 26 and the other end is connected to a Z-shaped clip 33 fastened to the terminal block assembly 18.

To remove the reflector pan 25 for cleaning, the heater unit 10 is grasped near the notch in the spider and pulled away from latching engagement by a slight horizontal movement to the right as seen in the drawings. This disengagement permits the heater unit 10 to be swung upwardly in a vertical arcuate motion. After the initial portion of this motion, the terminal portions 29 and 30 engage and rest upon the upper edges of the crossbar 28, which edges thus serve as a fulcrum or pivot for the remainder of the upward swinging movement. With the heater unit 10 in such raised position, the reflector pan 25 may be readily removed for cleaning.

In ordinary use, the support ring 20 remains in position and only the reflector pan 25 is removed for cleaning. Sufficient access to the ring and to the underside of the heater unit is obtained when the heater unit is swung upwardly and the reflector pan is removed.

When it is desired to disassemble the entire surface unit from the range platform, the reflector pan is first removed, as above described. The spring 32 is detached from the clip 33 and the support ring 20 is then also lifted from the platform. Then, the ring 20 is manipulated to bring the flange 24 above the outer ends of the arms of the spider 13. To do this, the flange 24 is first brought around to the top of the end of the spider arm 34, which may be done without any difficulty. The flange 24 is then brought around to the upper side of the free end of the spider arm 35. This may be easily done if the portion of the flange shown at 36 is brought above the adjacent portion of the tubular heater 11. Thereafter, the flange is brought above the upper end of the spider arm 31. The T-shaped bracket 26 may then be readily removed by first horizontally rotating the ring clockwise through a small angle about the T-shaped bracket as an axis and by positioning the crossbar and with-

drawing it through the space designated by the reference numeral 38 in Figure 1 and in Figure 6, such withdrawal being illustrated in Figure 6.

While I have shown my invention in but one form, it will be obvious to those skilled in the art that it is not so limited, but is susceptible of various changes and modifications without departing from the spirit thereof.

What I claim is:

- 10 1. An electric surface heating unit comprising a sheathed resistance heater disposed substantially in a horizontal plane and having its terminal portions disposed below said plane and adjacent each other, an annular ring supporting said sheathed heater, an inverted T-shaped member fastened to said annular ring, said T-shaped member having its vertical portion disposed between two terminal portions of said sheathed heater and having its crossbar extending beneath and adjacent said terminal portions, 15 said crossbar being longer than the space between said two adjacent terminal portions and adapted to engage said terminal portions and act as a support and fulcrum therefor upon upward arcuate movement of said sheathed heater relative to said annular ring.
- 20 2. An electric surface heating unit as set forth in claim 1, wherein said T-shaped member has a thickness substantially less than the space between said two adjacent terminal portions and is further of such limited dimensions that the T-shaped member may be withdrawn from the space between the terminal portions to permit separation of said heater from said ring.
